(57) CLAIM

The ornamental design for a beach umbrella stake, as shown and described.

DESCRIPTION

FIG. 1 is a perspective view of the beach umbrella stake embodying the design of the present invention.

FIG. 2 is a front elevational view thereof;

FIG. 3 is a rear elevational view thereof;

FIG. 4 is a side elevational view thereof;

FIG. 5 is a top plan view thereof;

FIG. 6 is a bottom plan view thereof; and,

FIG. 7 is a perspective view shown on a greatly reduced scale showing the beach umbrella stake inserted in a sandy beach and an umbrella inserted therein.

The broken line showing of environment is for illustrative purposes only and forms no part of the claimed design.
